UNITED STATES PATENT OFFICE.

ERICH H. LICHTENBERG, OF MILWAUKEE, WISCONSIN, ASSIGNOR, BY MESNE ASSIGNMENTS, TO KOEHRING COMPANY, OF MILWAUKEE, WISCONSIN, A CORPORATION OF WISCONSIN.

TRACTION GRADING MACHINE.

Application filed February 28, 1919. Serial No. 279,235.

To all whom it may concern:

Be it known that I, ERICH H. LICHTENBERG, am a citizen of the United States, residing at Milwaukee, in the county of Milwaukee and State of Wisconsin, have invented certain new and useful Improvements in Traction Grading Machines, of which the following is a specification.

The improvements of this invention apply to power driven grading machines, and the grader embodying said improvements is adapted particularly for cutting out road beds for the laying of new roads, for ripping out and loading old macadam, when breaking up old roads, and generally for grading purposes irrespective of road construction.

In addition to the excavating action of the machine, provisions are made for the elevation and dumping of the excavated materials onto a suitable conveyer designed to transfer the materials laterally from the grader into wagons, trucks, or cars.

The grader of this invention is of course designed primarily to reduce the cost of grading by the elimination of hand labor, and with a view to effecting the desired object, it is proposed by the present improvements to provide an especially designed excavating wheel of novel construction embodying peculiarly formed and arranged cutting and breaking up elements. The cutting and breaking up elements are intended to perform their functions with a high degree of effectiveness and with the expense of a minimum amount of power in their operation.

In the carrying out of the invention furthermore, the grading or excavating wheel is supported for adjustment vertically to throw it into and out of action, and to regulate the depth of excavation. A suitable frame is therefore employed to carry said grading wheel and an essential feature of novelty of the invention resides in utilizing gear or transmission devices for raising and lowering said frame and its supported grading wheel, which gear devices are dual in their functioning because not only are they

adapted to transmit movement required in respect to the elevating and lowering of the wheel, but they maintain the frame against lateral sway or movement, by a very rigid action. The said gear devices form lateral sway or play preventing means for said frame, not only in its vertical movement but such as might tend to be imparted thereto in the digging or excavating action of the excavating means of the grading wheel.

The grading machine of the invention is primarily supported upon caterpillar traction devices and said devices are of an improved type involving movement limiting means for the caterpillar tread supporting frame obviating any tendency of the tread to "dig in" when encountering a soft space in the area in process of being graded.

Another feature of the invention resides in the peculiar construction and arrangement of the lateral conveyer associated with the grading wheel and adapted to carry off the materials excavated. This conveyer is one adapted to be reversed so as to extend in a right angular direction from the machine projecting from one side or the other according to predetermined adjustment, and dependent upon the requirements of the work, the grading of which is to be done.

This invention involves other details of construction which will be understood upon reference to the following descriptions in connection with the accompanying drawings in which:

Figure 1 is a side view depicting in a somewhat diagrammatical manner the various general parts of the machine and their arrangement relatively to one another;

Figure 2 is a fragmentary plan view showing the means for turning the steering roller in opposite directions;

Figure 3 is an enlarged vertical sectional view taken through the excavating wheel and a portion of the body of the machine bringing out the construction of the buckets, the manner of mounting of the wheel on the movable frame by which it is supported, the arrangement of the conveyer, and the operating devices for raising and lowering said

frame, the latter consisting of herring bone sectors and pinions with suitable drive gearing;

Figure 4 is a fragmentary view in elevation of one of the herring-bone sectors, its matching pinion and certain driving parts;

Figure 5 is a vertical transverse sectional view through the machine about centrally of the grading wheel and illustrating the arrangement of the conveyer in full lines as extending from one side of the machine, and in dotted lines as when it is adjusted to project from the other side of the machine;

Figure 6 is a plan view, many parts omitted, bringing out more clearly the conveyer arrangement and showing in dotted lines a reversed disposition of the conveyer, supplementing the illustration of Figure 5 in this respect;

Figure 7 is a fragmentary view showing a section of the grading wheel and illustrating more fully the somewhat herring-bone formation of the excavating buckets, and the staggered arrangement of the digging teeth thereof;

Figure 8 is a side view showing a portion of the frame of the machine and one of the caterpillars supported thereby, the yielding connection between one end of the caterpillar frame and one end of the main frame being illustrated;

Figure 9 is a top plan view of the parts depicted in Figure 8;

Figure 10 is an end view of the caterpillar tread structure and operating gearing therefor;

Figure 11 is a side elevation showing in a diagrammatical manner the general arrangement of the parts of the machine, details of the latter being omitted to enable certain automatic clutch knockout mechanism to be clearly shown;

Figure 12 is a detailed view of the clutch knockout device proper, connections with the conveyer and main clutch lever at the motor being broken away.

Figure 13 is a perspective view of one of the buckets carried by the grading wheel, showing more particularly the detachable wear plate provided as a part of the inner portion of the bucket, to cooperate with the curved plate 38.

Throughout this specification and in the drawings, similar reference characters refer to similar parts.

As is usual in extremely large and cumbersome machines of the type of this invention there is provided a body somewhat in the form of a cab A, or similar enclosure, in which are mounted the motor instrumentalities, driving connections leading off to the traction and excavating devices for the machine. Since in many respects the controlling and motor driving mechanisms employed in this machine are of types com-

monly utilized in large power machines, such features are not illustrated in detail, and they will not be so described because different types of operating motors, controlling mechanisms including clutch devices, and trains of gearing are contemplated to be used within the purview of the invention.

Referring to Figure 1 therefore it is merely notable that the cab A contains a suitable motor 1, constituting a prime mover the shaft 2 of which is connected to drive a large gear 3 by means of a smaller gear 4. The gear 3 is carried by what will be called a main driving shaft 5, said shaft being geared to various other shafts in a manner to be hereinafter generally set forth, whereby to transmit power to different mechanisms of the machine. Exemplifying the foregoing, it will be noted that a lever 6 in the cab is arranged handy for action by the operator standing adjacent, whereby to throw clutch mechanism, not illustrated, so as to turn shaft 7 in either of opposite directions.

At its rear end the body of the machine is supported upon a steering roller B and at its front end said body is supported upon two or more spaced caterpillars C. The movable treads of the caterpillars C are turned by suitable driving connections including a sprocket chain 8 which engages a sprocket wheel 9, see Figures 1 and 8 to 10 inclusive. The sprocket chain 8 leads to a sprocket gear 10 upon a shaft 11. The shaft 11 is connected with the shaft 12 by suitable intermeshing gears, and the shaft 12 is similarly driven from the main shaft 5.

The grading or excavating wheel 13 is disposed at the front end of the machine, being carried by a frame 14 composed of spaced channels or fabricated in any suitable but substantial manner. The channels of said frame form its sides and are pivotally connected at 15 with the body of the machine, this connection allowing for an upward and downward movement of the frame 14 to correspondingly control movement of the grading wheel 13 supported hereby.

As seen best in Figures 1 and 5, a conveyer D is mounted so that a large portion thereof is surrounded by the structure of the excavating or grading wheel 13, an end of the conveyer projecting laterally from said wheel in such a manner that materials carried off by the conveyer may be disposed in wagons driven alongside of the machine, in cars or trucks, or upon the ground, if the conditions permit.

The steering of the machine is controlled by the instrumentalities illustrated in Figure 2, or any suitable means for the purpose. These instrumentalities include a shaft 16 geared so as to be operated from

the shaft 5. Another shaft 17 has a beveled gear 18 adapted to engage driving beveled gears 19 on the shaft 16. A conventional double clutch element 20 is shiftable by means not illustrated to connect either one of the gears 19 with the shaft 16. Thus, when the latter is driven the shaft 17 may be operated in either direction and its worm 21 is capable of turning the worm sector 22 in either direction, said sector being rigid on the spindle 23 projecting upwards from the yoke in which the roller B is journaled.

The excavating wheel 13 is best seen in Figures 3 and 5. This wheel consists primarily of a pair of rings 24 between which are arranged and to which are bolted each of a circularly disposed series of buckets 25. The buckets 25 are of angular shape, or for purposes of this description they will be characterized as herring-bone shaped buckets. Said buckets therefore have angular shaped cutting edges and said cutting edges become effective gradually in acting upon the surface to be cut, broken up, and excavated. Each bucket 25 is equipped with a series of digging teeth 26 and the digging teeth of one bucket are peculiarly arranged relatively to those of the next bucket by being staggered. The teeth of one bucket therefore enter the surface operated on at points between the places where the teeth of the next succeeding bucket enter the surface, as will be obvious from Figure 7 of the drawings. The structure in this respect is calculated of course to reduce the shock incident to entering of the cutting and digging elements into the surface being graded.

The method of supporting the grading wheel is by providing suitable rollers 27, see Figures 1, 3, and 5, carried by transverse shafts 28 of a length substantially the same as the width of the grading wheel. The shafts 28 are mounted in suitable bearings 29 in brackets 29, some of which extend downwards and some upwards from the supporting frame 14 on which the wheel 13 is carried. At opposite ends of the excavating wheel 13 and at the upper inner bearing 50 the brackets 29 are of special form in that they are constructed with extensions 29*, seen best in Figures 3 and 4, which extensions are provided with toothed sectors 30, the teeth of which are arranged analogous to the bones of a herring, for which reason said sectors will be hereinafter characterized as herring-bone sectors. Meshing with the sectors 30 are the herring-bone pinions 31 carried by a shaft 32 journaled on the main frame of the machine. On the shaft 32 is a large gear 33 meshing with a smaller gear 34 keyed to a shaft 35 on which is fixed a worm wheel 36. The wheel 36 is engaged by a worm 37 on the shaft 7 previously described. The shaft 7 is adapted to be driven

reversely from the shaft 5 under the control of lever 6. It will be seen therefore that a raising or lowering movement may be imparted to the frame 14 supporting the grading wheel, at the will of the operator and by means of the lever 6. The use of the herring-bone gearing devices 30 and 31 provides not only drive gearing for the above purpose, but these gearing devices obviously hold the frame 14 absolutely rigid against lateral sway, and counteract the tendency of obstructions beneath the surface operated upon to force the excavating wheel and the frame laterally.

The manner in which the buckets 25 are supported relatively to the rings 24 making up the frame work of the grading wheel will be seen in Figure 3 which also illustrates how the teeth and cutting portions of the buckets gradually enter the surface being operated upon. It is also notable that the material broken up, cut, and excavated by the buckets is kept in the buckets as they move upwards from their lowermost excavating position, by means of a curved plate 38 suitably supported by curved brackets 39, see Figure 3, attached to the frame 14 and to supporting angle plates 40 attached in any suitable manner to certain of the brackets 29, those located at the rear upper portion of the frame 14. The chani 15 which compose the frame 14 have transverse channels attached thereto as shown at 41 in Figure 3 and curved brackets 42 carried by said transverse channels support a conveyer 100 drive shaft 43 seen best in Figures 3 and 6. The conveyer operated by said shaft 43 is designated 44 and is of the endless belt type. The gearing for driving the conveyer 44 is shown best in Figures 5 and 6 and consists of a double beveled gear 45 on a shaft 46, one end of which projects beyond one side of the frame 14, see Figure 5, and carries a sprocket gear 47. A sprocket chain 48, seen diagrammatically in Figure 1, connects the sprocket wheel 47 with a corresponding wheel on the main shaft 5. The drive therefore is taken off the main shaft 5 and communicated to the shaft 46 from which it is communicated to the shaft 43 of the conveyer by means of the double beveled gear 45 which meshes with the beveled gear 49. On its end opposite that carrying the gear 49 the shaft 43 has a sprocket wheel 50 connected by a sprocket chain 51 with a sprocket wheel 52 on the roller shaft 53 at the outer extremity of the conveyer 44. The inner roller shaft of the conveyer 44 is shown at 54 in Figure 5. The manner in which the materials excavated and elevated by the buckets 25 are disposed on the conveyer is seen best in Figure 3 and the action of the conveyer in carrying off said materials is obvious.

In Figure 6 there is illustrated by dotted

lines a rearrangement of the gearing and conveyer parts such as takes place when the conveyer is to project from the side of the machine opposite that in which it is shown in full lines in Figures 5 and 6. Figure 5 also affords a partial showing of the rearrangement, see dotted lines. The rearrangement aforesaid involves merely removal of the bearing 45^a for the gear 45 and shifting same a short distance to the left, and a sliding through the excavator wheel of the whole conveyer 44 and its supporting parts and a redisposition of the shaft 43, as shown in dotted left adjustment of Fig. 6, so that its gear 49 is disposed on the opposite side and in mesh with the other face of the beveled gear 45. The shaft 43 under these conditions is shifted to occupy the right dotted line position relative to the conveyer 44 in which they and the shaft are shown in Figure 6.

In addition to the buckets 25 it will be seen that the rings 24 carry on their outer sides outwardly and downwardly curving buckets 55, the action of which is to cut curved edge portions for the ditch or excavation which is made by the grading wheel when in operation.

The grading wheel itself may be caused to turn by any suitable driving mechanism, that illustrated including the employment of gears on one or more shafts 56, see Figure 1, which gears mesh with teeth 57 with which the outer sides of the rings 24 are equipped, a sprocket chain 58 leading from a sprocket gear on the shaft 56 back to a corresponding gear on the main shaft 5. Obviously, a different type of driving mechanism might be employed in the above connection, the one suggested and diagrammatically illustrated in Figure 1 being really typical of such as may be used.

Referring to Figures 8 to 10 inclusive, the caterpillar will be seen to comprise a frame made up of spaced channel beams forming sides 59, at opposite ends of which are arranged the shafts 60 on which are mounted the rollers 61 about which the caterpillar tread 62 operates. The front shaft 60 carries a large gear 63 meshing with a smaller gear 64 on a shaft 65 which forms a sort of rocker bearing for the whole caterpillar, said shaft passing through the sides of the caterpillar frame near the rear end portion of the latter. The shaft 65 is supported by suitable brackets 66. The turning of the caterpillar tread is effected by operation of the gear 64 through the sprocket chain 8 previously mentioned, which sprocket chain passes about the gear 9 fixed on the shaft 65, adjacent to the gear 64, all as seen best in Figures 8 to 10 inclusive. The front end portion of the frame of each caterpillar C is yieldingly supported by a spring equalizing device

consisting of vertical bars 67 which are surrounded by flanged sleeves 68 engaged by springs 68^a adapted to move up and down in brackets 69, seen best in Figure 10. The lower ends of the bars 67 are attached to brackets 70 at opposite sides of the frame 59. It will be obvious that the front end of the frame of each caterpillar is yieldingly held in its proper position for ordinary operation. Owing, however, to the arrangement and movability of the sleeves 68 the front portion of each caterpillar is adapted for slight upward and downward movement.

Where nearly filled sewer ditches or like soft spots are met with in the movement of the machine the tendency of ordinary caterpillars is to dig in to said spots, and this tendency is avoided by the construction above set forth.

Figure 11 illustrates diagrammatically an automatic mechanism for disengaging the clutch by which the drive is taken off from the motor to operate the grading wheel 13, and the conveyer D. The two conditions under which said means operates are these, namely, where in the turning of the grading wheel an obstruction is met with larger than can be handled by the conveyer D, even though it might be elevated by the buckets 25, it is desirable that the operation of the wheel be stopped to prevent clogging of the machine; second, in the event that during raising of the conveyer the maximum degree of elevation of the latter is reached stopping of the movement of the conveyer upwards is advantageous in order to avoid liability of breakage of parts.

The conveyer D is adapted to be raised and lowered by a cable 71, seen in Figures 1 and 5. It is connected with a bail 72 directly attached to the frame of the conveyer. The cable 71 leads over a pulley 73 on a framewise structure 74, thence over a pulley 75 at the upper portion of the cab A, then under a pulley 76 near the floor of the cab back to a drum 76^a on the shaft 15 adapted to be driven by a worm 77 on the shaft 78. The shaft 78 may be driven from the shaft 16 by suitable means not shown, or from any other source of power.

The clutch knockout mechanism, see Figures 11 and 12, consists of a shaft 79 having thereon a series of feeler arms 80 projecting towards the buckets of the wheel 13 so that an unusually large obstruction, say a rock or a piece of asphalt, will strike said arms 80. Two arms 81 rigid on the shaft 79 project downwardly therefrom and are connected by a rod 82. A single arm 83 projects upwardly from one end of the shaft 79. The arm 83 is connected by a cable 84 which leads to the clutch lever 85 adjacent the motor 1. A second cable 86

- leads from one of the arms 81 to a point of connection with the frame of the conveyer D. Obviously an obstruction meeting any one or more of the feeler arms 80 will 5 raise said arms and rock the shaft 79. In this manner a pull will be exerted on the cable 84 and the clutch 85 automatically shifted to clutch disengaging position stopping the drive mechanism by which the 10 wheel 13 is actuated. Again, if the drum 76^a is being turned to raise the conveyer D, at a certain point in such raising movement, a pull will be exerted on the cable 86 and the shaft 79 rocked in a manner like that 15 above described, with the same result effected, namely, stopping of the drive means by which the conveyer is being actuated.
- No danger of injury to the conveyer or surrounding adjacent parts is thus likely.
- 20 The buckets 25 are of peculiar construction in that each bucket embodies a detachable wear plate 25^a, said plate contacting with the curved plate 38 which forms a somewhat drum-like structure about which 25 the buckets revolve. The buckets 25 are formed at their ends with lugs 25^b to which the plates 25^a are directly fastened in a substantial but a detachable manner. Figure 30 13 shows clearly the detail bucket construction and also certain additional lugs 25^c for attaching the buckets to the rings 24.
- Having thus described my invention, what I claim as new is:—
1. In a grading machine of the class described, the combination of a movable support, a grading device mounted thereon, and a single means for raising and lowering said grading device, and for preventing lateral movement of the same.
  2. In an excavating and grading machine of the character described, the combination with a main support, of an excavating and grading device, an adjustable frame mounted upon the main support and carrying the 45 excavating and grading means, and gearing having intermeshing teeth arranged at opposite inclinations whereby the gearing serves both to adjust the position of the frame and to hold the frame against lateral displacement.
  3. In a grading machine of the class described, the combination of a movable support, a grading device mounted thereon, gearing intermediate the support and the 55 grading device, comprising meshing herringbone pinion and toothed sector parts, and means to operate said gearing to elevate or lower the grading device, the herring bone gearing also preventing lateral displacement of the grading device.
  4. In a grading machine, the combination of a wheeled support and means whereby the same may be propelled, a rotary grading device carried by said support, a frame supporting the grading device and pivotally 60 connected with the wheeled support aforesaid, and means to raise and lower said frame relatively to the wheeled support, and correspondingly adjust the grading device, comprising a toothed sector connected with the frame and an operating pinion engaging said sector, the teeth of the sector and pinion having a herring-bone arrangement substantially as described whereby the grading device is held against lateral displacement. 70
  5. Grading means of the class described, comprising a frame, a grading device rotatively mounted thereon including spaced rings and excavating devices connected to and carried by said rings, rollers on the frame supporting and forming anti-friction bearings between the frame and the rings, the engaging portions of said rollers and rings being beveled in order to center the grading device in its rotary movement and 80 in order to prevent cutting action of the rollers relatively to the contacting portions of the rings.
  6. Grading means of the class described, comprising a frame, a grading device rotatively mounted thereon including spaced rings and excavating devices connected to and carried by said rings, rollers on the frame supporting and forming anti-friction bearings between the frame and the rings, the engaging portions of said rollers and rings being beveled in order to center the grading device in its rotary movement and 85 in order to prevent cutting action of the rollers relatively to the contacting portions of the rings.
  7. A grading device of the character described, including a rotary drum, and a series of excavating buckets mounted thereon in a peripheral series, said buckets being formed with V-shaped entering edges arranged in planes substantially tangential to the drums, and adapted to gradually enter the work from their first entering portions.
  8. A grading device of the character described including a rotary drum, transversely disposed excavating buckets mounted thereon in a peripheral series, each bucket having its entering edges of a formation reversely angled from a median point with respect to a line of cut at right angles to the direction of movement of the device to thereby progressively apply its cutting edge to the work.
  9. A grading device of the class described comprising a wheel structure embodying spaced rings, buckets connected at their opposite ends to said rings, and arranged in spaced relation, each bucket ha 100

- gular cutting edge arranged in a substantially tangential relation to the wheel structure, the series of buckets thereby presenting a sort of herring-bone construction, and
- 5 15. A grading machine of the character described including a rotary drum, excavating buckets arranged thereon in a peripheral series, means for driving the drum, trip means arranged adjacent the path of the buckets for engagement with unusually large pieces of excavated material, and means actuated by the said trip means for controlling the before mentioned drive means.
- 10 16. A grading device of the character described, including a rotary drum, a peripheral series of excavating buckets thereon, means for driving the drum, a rock shaft, feelers projecting from the rock shaft toward the path of the buckets for engagement with large pieces of excavating material, and means actuated by the rock shaft for governing the before mentioned drive means.
- 15 17. A grading machine of the character described comprising a conveyer, a movable frame supporting the conveyer in operative position, power means for adjusting the position of the conveyer, a trip member mounted on the machine, stop mechanism for discontinuing operation of the power means for the conveyer, an actuating connection between the conveyer frame and the trip member, and a connection between said trip member and the stop mechanism whereby the latter may be operated through the trip member from the conveyer frame.
- 20 18. In a grading machine, the combination of an excavating device, a conveyer, power means for adjusting the position of the conveyer and actuating the excavating device, stopping means for discontinuing the operation of the excavating device and the adjustment of the conveyer, and trip means common to the conveyer and excavating device whereby to automatically stop either the excavating device or the adjusting movement of the conveyer under abnormal operations of these parts.
- 25 19. In a grading machine, the combination of an excavating device, a conveyer, power means for adjusting the position of the conveyer and for actuating the excavating device, stopping means for discontinuing the operation of the excavating device and the adjustment of the conveyer, a trip member for controlling the stopping mechanism aforesaid a connection intermediate the trip member and the stopping mechanism, and a connection between said trip member and the conveyer, said trip member being operable incident to an abnormal movement of the conveyer or from the excavating device in an abnormal excavating operation of the latter.
- 30 20. In a grading machine, the combination of an excavating device, a conveyer, power means for adjusting the position of the conveyer and for actuating the excavating device, stopping means for discontinuing
- 10 11. In an excavating and grading machine, the combination of an excavating and grading device, means to operate the same, stopping means for discontinuing operation of the excavating and grading device, and trip means in the path of certain materials excavated by the grading device for operating the stopping means.
- 15 12. In an excavating and grading machine, the combination of an excavating and grading wheel having excavating buckets, operating means for the wheel, means to govern the action of said operating means, and trip mechanism including feeler arms projecting toward the wheel and adapted to be actuated by large obstructions handled thereby to actuate the governing means.
- 20 13. A grader of the character described, including a rotary drum, excavating buckets mounted thereon in a peripheral series, the inner ends of the buckets opening into the drum, an apron arranged within the drum to close the inner ends of the buckets during a portion of the movement thereof, the portions of the buckets which engage the apron being detachable, and conveying means receiving the material discharged from the buckets when they reach the end of the apron.
- 25 14. A grading device of the character described, including a rotary drum, buckets mounted thereon in a peripheral series and opening at their inner ends into the drum, said inner ends of the buckets being formed with separate detachable plates, a curved apron arranged within the drum for cooperation with the said plates to close the inner ends of the buckets during a portion of the movement thereof and permit the buckets to discharge into the drum at a predetermined position, and means for receiving the material thus discharged.
- 30 15. A grading machine of the character described including a rotary drum, excavating buckets arranged thereon in a peripheral series, means for driving the drum, trip means arranged adjacent the path of the buckets for engagement with unusually large pieces of excavated material, and means actuated by the said trip means for controlling the before mentioned drive means.
- 35 16. A grading device of the character described, including a rotary drum, a peripheral series of excavating buckets thereon, means for driving the drum, a rock shaft, feelers projecting from the rock shaft toward the path of the buckets for engagement with large pieces of excavating material, and means actuated by the rock shaft for governing the before mentioned drive means.
- 40 17. A grading machine of the character described comprising a conveyer, a movable frame supporting the conveyer in operative position, power means for adjusting the position of the conveyer, a trip member mounted on the machine, stop mechanism for discontinuing operation of the power means for the conveyer, an actuating connection between the conveyer frame and the trip member, and a connection between said trip member and the stop mechanism whereby the latter may be operated through the trip member from the conveyer frame.
- 45 18. In a grading machine, the combination of an excavating device, a conveyer, power means for adjusting the position of the conveyer and actuating the excavating device, stopping means for discontinuing the operation of the excavating device and the adjustment of the conveyer, and trip means common to the conveyer and excavating device whereby to automatically stop either the excavating device or the adjusting movement of the conveyer under abnormal operations of these parts.
- 50 19. In a grading machine, the combination of an excavating device, a conveyer, power means for adjusting the position of the conveyer and for actuating the excavating device, stopping means for discontinuing the operation of the excavating device and the adjustment of the conveyer, a trip member for controlling the stopping mechanism aforesaid a connection intermediate the trip member and the stopping mechanism, and a connection between said trip member and the conveyer, said trip member being operable incident to an abnormal movement of the conveyer or from the excavating device in an abnormal excavating operation of the latter.
- 55 20. In a grading machine, the combination of an excavating device, a conveyer, power means for adjusting the position of the conveyer and for actuating the excavating device, stopping means for discontinuing

ing the operation of the excavating device and the adjustment of the conveyer, a trip member arranged contiguous to the excavating member, an actuating connection between said trip member and the stop mechanism, and an actuating connection between the conveyer and said trip member, said stop mechanism being operable by the trip member incident either to contact therewith by material from the excavator or abnormal 10 adjustment of the conveyer.

In testimony whereof I affix my signature.

ERICH H. LICHTENBERG.
